[57] ABSTRACT

The novel control device is adapted to be attached to

a sewing machine having a rotary drive means driving a vertical needle bar mounted for reciprocation between an upper and lower position with respect to a looper located below the needle. The machine has a transmission system operably connected between the rotary drive means and the needle bar. The transmission system includes a lever pivotably mounted between its ends and pin connected at one end to the needle bar. The other end is connected to a crank on the rotary drive means through a pitman that is pin connected therebetween. In addition, the crank is operably connected to a looper for synchronously driving the looper with the needle bar. The transmission system also includes the control device in the form of two pin-connected links connected between a fixed pivot point and the pin connection of the crank and the pitman. Means are provided to pivot the respective link about the fixed point between two positions, one of which allows the lever to idle. On this respective link is formed a cam that cooperates with a lug on the lever that prevents the respective link to move from the first to the second position unless the needle bar is in its upper position.

RECIPROCATING MOTION CONTROL DEVICE

FIELD OF THE INVENTION

This invention relates to a means for stopping reciprocating motion of a work element, and more particularly to means for stopping a work element in a predetermined position.

BACKGROUND OF THE INVENTION

In the art of automatic operations, particularly in the garment industry using conventional sewing machines, it is often necessary to position the sewing needle in an up position with respect to the sewing surface and looper. The up position is required when the operator wishes to remove the work or to make necessary thread adjustments and to lock the thread to itself to prevent unravelling. Usually, the needle bar would not end up in a desired up position and the operator, with conventional machines, is required to manually adjust the machine to raise the needle bar to the desired position by turning the flywheel of the sewing machine. This relatively slow, manual adjustment consumes a great deal of the operator's time and substantially increases the cost of the article being manufactured. The prior art teaches to eliminate the manual adjustment of the sewing machine by utilizing automatic or semi-automatic mechanical or electrical stop motion devices with sewing machines. However, most of the previously proposed devices are of substantially complex construction, requiring extensive modifications of the sewing machine itself, and in some cases are suitable only for particular types of sewing machines. A number of such previously proposed devices uses auxiliary motors and clutches to rotate the flywheel of the sewing machine to the proper position. Other devices utilize electronic control circuits for the drive motor of the sewing machine or for engaging and disengaging pawls and cams attach to the drive shaft of the sewing machine. Still other previously proposed devices which have been utilized in the field are relatively expensive and complicated in construction. Further, the sewing machine utilizes cams and pawls in their stop motion devices which produces excessive shock to the machines which often results in breakage, distortion and undue wear of the parts.

OBJECT OF THE INVENTION

An object of this invention is to provide a means for stopping the reciprocating motion to a tool at a predetermined point.

Another object is to provide a simple, dependable means for stopping a reciprocating motion of a tool at a predetermined point.

Another object is to provide a means for stopping reciprocating motion of a tool at a predetermined point, without developing excessive shock and jarring of the machine parts.

These and other objects and features of advantage will become more apparent after studying the following description of the preferred embodiment in conjunction with the appended drawing.

BRIEF DESCRIPTION OF THE DRAWING

FIG. 1 is a side section elevation of a sewing machine schematically showing the internal, mechanical linkages with the novel stopping means positioned during reciprocation of the needle bar.

FIG. 2 is also a side section elevation of the machine in FIG. 1 with the novel stopping means positioned while the needle bar is stopped in the up position.

10 DETAILED DESCRIPTION OF THE DRAWINGS

Referring to the drawing, there is shown schematically a sewing machine 10, embodying the novel means of the present invention. Machine 10 has a housing 12 which encloses an electric motor 14 that provides power to the sewing machine to reciprocate a vertically disposed needle bar 16 during the sewing operation, through a standard transmission system 18. The system 18, besides reciprocating the needle bar up and down, also actuates a looper 24 synchronous with the needle 26 on the end of bar 16. To provide loop stitching as is common in the art. The system 18 includes a flywheel 20 rotated by the motor 14 about an axis normal to the drawing. To the flywheel 20 is connected a crank arm 28 by a pin 30. A pitman 34 is connected at one end to arm 28 by a pin 32, and at the other end to one end of a lever arm 36 by pin 40. The lever arm 36 rocks about a stationary pin 37, located between its end and has the other end pin connected to a link 35 that is in turn pin connected to the needle bar 16. Thus, as motor 14 rotates the flywheel 20, the lever arm 36 is rocked up and down about pin 37 and the needle arm 16 and needle 26 reciprocate up and down in the plane of the drawing.

35 To actuate the looper 24 synchronous with the needle 26 an extension arm 72 is integrally formed to the pitman 34, substantially as shown, and has its upper end connected to a transmission link 76 by a pivot pin 74. The link 76 depends from pin 74 and has its lower end connected to a crank arm 80 by a pivot pin 78. The link 76 is shown broken away to show the details behind the link 76. The arm 80 is disposed to rotate about a fixed shaft 79 and has, integral therewith, a bevel gear 77. Another bevel gear 61 measures with gear 77 to provide reciprocating, rotational motion to a transmission shaft 62 that is suitably journaled within the housing 12 to rotate about its own axis. The looper 24 is connected to the opposite end of shaft 62. The description of the transmission system 18, up to this point, is standard in the art.

50 The novel means that allows the pitman 34 to reciprocate the needle bar or to stop the needle bar 16 while the motor 14 keeps running will now be explained. To reciprocate the lever arm 36, the line of thrust of the pitman should be substantially perpendicular to the arm 36 and therefore pitman 34 should be substantially perpendicular to arm 36. The pitman is held in this position by a control linkage that includes a controlled lever 52 pin connected to the housing 12 by a stationary pin 54 at one end thereof. The lower end of lever 52 is pinconnected connected to a control link 55 by a pin 56. The other end of link 55 is pin-connected to the pin 32. The control lever 52 is disposed in front of the lever arm 36 as viewed in the figures so that the lever 52 and arm 36 are mathematically in a skew position. The arm 36 preferably oscillates in a plane parallel to the control lever. The control lever 52 is held in

its first position, as shown in FIG. 1, by a connecting rod 57 extending from the air piston and cylinder assembly 58. When pressure is applied to assembly 58, the rod 57 is pulled to the left, as viewed in the drawing, to swing the control lever 52 to the second position, as shown in FIG. 2. This causes the control link 55 to pivot with respect to the pitman 34 so that the pitman is no longer perpendicular to the lever arm 36, thereby stopping its oscillation.

To insure that the pitman 34 and control link 55 are in the position shown in FIG. 2, that is, parallel to each other so that the needle bar 26 is in the up position, a cam 59 is conveniently mounted on the control lever 52, while on lever arm 36 there is placed a lug 38. The cam 59 is formed with a camming surface 60 that is cylindrically shaped, having its center at the axis of the pin 37 when the control lever 52 is in the first position as shown in FIG. 1. A space of a few thousandths of an inch is between surface 60 and lug 38. The purpose of this spacing is that the lug 38 on lever arm 36 is free to oscillate up and down without friction therebetween while motor 14 is rotating with the control lever 52 in the first position. To place the control lever 52 in its first position the air pressure is released for example from the piston and cylinder assembly 58.

When the control lever 52 is moved from its first position to its second position, the needle bar 16 stops oscillating. As mentioned above, this function is done by applying fluid pressure to assembly 58 to pull the connecting rod 57 to the left. However, with the camming surface 60 on cam 59, and with lug 38 of lever arm 36, the control lever 52 cannot move to its second position until lug 38 is free of the camming surface 60, i.e., when in its down position. Thus surface 60 is made so that it ends above lug 38 when the lug is in its lowest position.

When the piston and cylinder assembly 58 is actuated to pull the control lever 52 to the left, to its second position, the lever 52 would not move if needle bar is not in its up position because the lug 38 would be in the way of the camming surface 60. Only when the lug is below the cam 59 could the control lever 52 move to its second position. Since the length of the pitman 34 and the length of the control link 55 are preferably the same, pins 40 and 56 will be aligned when the control lever 52 is in its second position. The control lever 54 is made with a bight portion 52a to allow this alignment. This fixes the position of both pins 40 and 56 so that the pitman 34 only oscillates about pin 40 as the motor 14 rotates. The cam 59 is provided with another surface 73 that meets the surface 60 to form a point as shown. The function of surface 73 is to insure that the lug 38 slides down to and around the point when the control lever is being moved to its first position to start sewing. Thus, the sewing machine is provided with a simple, inexpensive means for always stopping the needle 26 in its up position.

Although one embodiment of the invention has been shown and described, the invention is not to be consid-

ered limited to the disclosed embodiment, for one skilled in the art, after studying this disclosure, could conceive other embodiments without departing from the spirit of the invention. Therefore, the invention is not limited to the disclosed embodiment but is limited to all embodiments, including those within the scope of the claims.

I claim:

1. In a device for converting rotary to reciprocating motion comprising:

a rotary drive means;

a work element mounted for reciprocation between first and second locations;

a lever arm pivotably mounted intermediate its ends and connected at one end to said work element;

a crank arm pivotably connected at one end to said rotary drive means;

a pitman, pivotably connected between said crank and the other end of said lever, to convert the rotary motion of said drive means to an oscillating motion on said lever arm;

a control lever pivotably mounted to said device and disposed to be skew with said lever arm;

first means for selectively moving said control lever between a first and second position;

a control link pivotably connected at one end to said control lever and at its other end to said crank arm at said point of connection between the crank arm and said pitman; and

said control lever and said control link cooperating in said first position to hold the line of thrust of said pitman substantially perpendicular to said lever arm to oscillate it, and cooperating in said second position, to hold the line of thrust of said pitman substantially in a line with said lever arm to hold it stationary;

the improvements comprising:

a lug formed on said lever arm and disposed between said other end of said lever arm and its pivotal mount;

said control lever having a cam, with a cylindrical camming surface disposed to cooperate with said lug; and

said cylindrical camming surface having its center of curvature disposed at the pivotal mount of said lever arm and said surface extends a distance shorter than the arcuated travel path of said lug whenever the control lever is in said first position.

2. In the device of claim 1 wherein:

said cam is limited to being elongated and fixed at one end to said control lever and disposed at an angle thereto so as to point toward said control link; and

said cam having a length such that when said lever arm is at one end of its travel, said cam is capable of clearing said lug when said control lever is being moved by said first means from said first position to said second position.
